HEEL ARCH COMPANY, OF BROCKTON, MASSACHUSETTS, A CORPORATION OF
MASSACHUSETTS.

INNERSOLE.

1,088,629.

specification of Letters Patent. Patented Feb. 24, 1914.

Application filed September 20, 1910. Serial No. 582,834.

To all whom it may concern:

Be it known that I, GEORGE E. ROLLINS, a citizen of the United States, residing at Brockton, in the county of Plymouth and 5 State of Massachusetts, have invented new and useful Improvements in Innersoles, of which the following is a specification.

This invention relates to improvements in boots, shoes and the like and relates particularly to improvements in and relating to 10 the inner sole.

The object of my invention is to provide an inner sole composed of two or more layers of leather or other suitable material 15 and having a nail clenching plate interposed between two of these layers and secured to the lower one, this plate serving to clench the heel nails and lasting tacks which are driven through the lower layer of the inner 20 sole. By the use of this plate, the heel nails and lasting tacks are prevented from passing through the upper surface of the inner sole and the upper surface is left perfectly smooth and requires no covering.

25 One important feature of my invention is that the nail clenching plate is secured to the lower layer of the inner sole and the lower layer of the inner sole is secured to the upper layer and to the last by a tack extending 30 through a perforation provided in the clenching plate and in this way both the clenching plate and the lower layer of the inner sole are prevented from moving laterally during the lasting operation. This is 35 an important point, since these parts if they were to move laterally would distort the shoe at that point. It is also important for the reason that if the plate were to become displaced laterally, some of the lasting tacks 40 might not be clenched against the bottom of the plate, but would pass beyond the plate into and through the upper layer of the inner sole. If this should occur, the points of the tacks would appear on the 45 inner or upper surface of the inner sole and this would, of course, be objectionable. Still another advantage derived from securing the plate to the lower layer of the inner sole is that when the shoe is completed 50 the plate holds the heel counter firmly around the edges and makes the shoe stronger as well as preventing the counter from crowding to one side.

55 Preferably, the lower layer of the inner sole is located at the heel portion only and

terminates adjacent to the shank portion. This has the advantage of permitting the use of an ordinary commercial inner sole with the nail clenching plate and the short layer of material secured thereto. It also 60 permits the use of a shank stiffener either formed on or secured to the clenching plate or as a separate part.

To these ends, my invention consists in the novel features of construction and in the 65 combination and arrangement of parts set forth in the following specification and particularly pointed out in the claims.

Referring to the drawing: Figure 1 is a perspective view of a shoe having an inner sole embodying my invention, the upper being partly broken away and the heel portion of the inner sole being lifted to show the nail clenching plate. Fig. 2 is a bottom plan of an inner sole embodying my 75 invention. Fig. 3 is a sectional view taken on line 6—6 of Fig. 2.

Like numerals refer to like parts throughout the several views of the drawing.

In the drawings, 18 is an inner sole which 80 is preferably composed of two or more layers, two layers 19 and 20 being shown in the drawing, the former being like the usual commercial leather inner sole and provided with a lip 21, for the attachment of a welt 85, and the layer 20 being preferably very short and located only at the heel portion.

Interposed between the layers 19 and 20 is a clenching plate 22 formed of any suitable material, preferably metal, said plate 90 being preferably secured to the layer 20 in any suitable manner as, for example, by providing said plate with integral tongues 23 driven through said layer and clenched on the under side thereof. The plate is preferably provided with a perforation 24 permitting tacks to be driven through the insole into the last to position the inner sole thereon preparatory to the operation of pulling over and lasting the upper. The tack or tacks thus driven into the layer 19 serve to secure the layer 20, as well as the plate 22, to the layer 19 during the making of the shoe. When the shoe is completed, however, the layer 19 is lifted as shown in Fig. 1, and the tack is clenched, after which the layer 19 is again laid down in place, thus leaving an inner sole entirely free from nails or tacks.

25 is a shank stiffener which may be

formed separate from the clenching plate 22 and this shank stiffener may be secured to a shank piece 26 in any suitable manner as by means of tacks 27 in the usual manner.

5 In order to illustrate clearly how the clenching plate appears when in a shoe as completed, I have shown the completed shoe in perspective in Fig. 1, the upper of the shoe being partly broken away to expose 10 the interior at the heel portion and the upper layer 19 of the inner sole being lifted to expose the clenching plate which underlies the same.

When the shoe has been lasted and leveled, 15 a heel is applied thereto in the usual manner by driving heel nails through the outer sole, through that portion of the upper which projects inwardly upon the upper face of the outer sole and through the lower 20 layer 20 of the inner sole, the inner or upper ends of the nails clenching against the plate 22. In this way, the heel nails as well as the lasting tacks which, of course, are also clenched against the bottom of the 25 plate, since they terminate below the entire upper layer 19 of the inner sole are protected by the upper layer and by the clenching plate and cause no discomfort to the heel of the wearer. Moreover, by this construction, the use of the supplementary lining of the inner sole is obviated.

Having thus described my invention, what

I claim and desire by Letters Patent to secure is:

1. An inner sole for boots and shoes having, in combination, two superposed distinct pieces of material one of which is longer than the other and extends from heel to toe and the other of which is located at the heel portion only, a nail clenching plate interposed between said pieces, and means extending from said plate into interengagement with the last-mentioned piece and rigidly fastening said plate thereto. 35

2. An inner sole for boots and shoes having, in combination, two superposed distinct pieces of material one of which is longer than the other and extends from heel to toe and the other of which is located at the heel portion only, a nail clenching plate interposed between said pieces, means extending from said plate into interengagement with one of said pieces and rigidly fastening said plate thereto, and a shank stiffener extending along the shank portion of said longer layer and beyond the front end of the shorter layer. 40 50

In testimony whereof I have hereunto set my hand in presence of two subscribing witnesses.

GEORGE E. ROLLINS.
